Teletype Corporation, Chicago, Ill., a corpora-
tion of Delaware

Application September 20, 1941, Serial No. 411,666

11 Claims. (Cl. 178—11)

This invention relates to telegraph transmission systems and more particularly to facsimile printing telegraph systems operable to print successive lines of a received record on a page of record material.

It is an object of the present invention to provide a single transmission system including a compact telegraph recorder operable to record successive lines of a record on record material.

In accordance with one embodiment of the invention the system includes, at the transmitting station, in addition to the usual transmitting equipment which may be of the type disclosed in the patent application of R. E. Zenner, Serial No. 209,523, filed May 28, 1938, apparatus for interrupting the transmission of messages by stopping the feeding of a tape to a tape controlled transmitter at predetermined intervals determined by the number of characters in a line of typing being typed on a page at the receiving station. This interruption of the transmission will permit relative movement between the paper and a part of the facsimile printing apparatus at the receiving station for effecting the line feeding operation and the carriage return operation at the receiving station or receiver. In the specific embodiment of the invention disclosed herein, the equipment at the receiving station includes a carriage supported traveling speaker motor having a knife-edged vibratable platen member supported for movement across the rear of a web of paper and responsive to received signals for forcing the paper against a scanning tape or cooperating movable platen having embossed ridges formed on it and moving across the face of the web of paper. The scanning tape has associated with it ink transferring rolls for supplying ink to the embossed ridges and also has a stiffening plate for holding the tape in a predetermined position when the paper is forced against the tape upon the receipt of a signal by the vibratable platen actuator. During the receipt of signals by the receiving apparatus, the speaker motor carriage is clutched to a driving mechanism for a predetermined time governed by the width of the paper, and automatic means are provided for releasing the clutch when the carriage which supports the speaker motor moves the motor to the end of a line, thereby to permit the carriage to return and the line feeding mechanism for feeding the paper to operate.

A better understanding of the invention may be had by reference to the following detailed description when considered in conjunction with the accompanying drawings wherein;

Fig. 1 is a plan view of apparatus embodying the invention, parts being broken away to illustrate more clearly those parts which would otherwise be hidden by the broken off portions;

5 Fig. 2 is a vertical sectional view taken along the lines 2—2 of Fig. 1 in the direction of the arrows showing parts of the apparatus in a side elevation and showing other parts broken away to illustrate more clearly details of the invention;

10 Fig. 3 is a rear elevational view of the apparatus shown in Figs. 1 and 2, the view being taken somewhat forward of the back of the machine to illustrate more clearly the mechanism for returning the speaker motor carriage to normal position after it has traversed a sheet or web of paper being passed through the apparatus during the receipt of a message, and

15 Fig. 4 is a schematic view of the circuit provided in the receiving apparatus shown in Figs. 1, 2, and 3, together with a diagrammatic view of the apparatus and circuits at the sending or transmitting station which interrupt transmission at that station during the carriage return at the receiving station.

20 Referring now to the drawings wherein like reference characters designate the same parts throughout the several views, particular reference being had at this time to Fig. 1, it will be noted that there is provided a motor 10 which drives the various motor driven parts of the apparatus. The motor 10 drives shaft 11 and through a gear 12 drives a shaft 13 suitably mounted in bearing brackets 14 and 15 and carrying gears 16, 17, and 18, the gear 18 meshing 25 with gear 12 on driving shaft 11.

The motor 10 is suitably mounted in spaced relation to a base member 19 which has extending upwardly from it at its outer edges, a pair of side plates 20 and 21. The bearing brackets 30 14 and 15 extend outwardly from the side plate 20 and thus support the shaft 13 in spaced relation thereto. The side plates 20 and 21 are interconnected by a cross member 22 which serves to brace them, and it also serves as a track for

35 a carriage 24 to be described in detail herein-after. Cooperating with the cross member 22 is a cross rod 23 positioned above the cross member 22 and serving as the other element of the track which supports the carriage. The carriage 24 has its upper ends, Figs. 2 and 3, bent toward the rear of the apparatus as shown most clearly in Figs. 1 and 2 to form guide lugs 25 and 26. These lugs 25 and 26 are apertured to receive the cross rod 23 and thus slidably support the carriage 24 on the cross rod 23. At the bottom of

40 45 50 55

the carriage 24 there is provided a roller bracket 27 which rotatably supports a roller 28 for engagement with the cross member 22. At its upper end the carriage 24 has an angle member 29 fixed to it, to which in turn there is fixed a rack 30 which meshes with a pinion 31, on the upper end of a shaft 32. The shaft 32 has slidably keyed to it a driven clutch member 33 on which there is formed a shoulder 34 for engagement by the opposite arms 35 of a bifurcated portion of a pivoted armature 36. The armature 36 is pivoted on an upwardly extending projection 37 of a plate 38 which extends between the side plates 20 and 21 and serves to support the motor 10 as well as the electromagnet 39 which actuates the armature 36.

Positioned for cooperation with the driven clutch member 33 is a driving clutch member 50 which is fixed to a shaft 51. The shaft 51 is journaled in a bearing 52 anchored in the plate 38 and the shaft 52 carries at its lower end a gear 53 meshing with a gear 54 on the end of shaft 55. Shaft 55 is journaled in the side plate 20 and in a bearing bracket 56 supported by cross member 22. The outer end of the shaft 55 (the left-hand as viewed in Fig. 3) carries a gear 57 meshing with a gear 58 on the lower end of a shaft 59. The upper end of the shaft 59 carries a gear 60 (Fig. 1) in mesh with the gear 17 on shaft 13, and the shaft 59 is supported at the right side of the machine as viewed in Fig. 1, or the left side as viewed in Fig. 3, by a pair of bearing brackets 61 and 62 fixed to the side plate 20.

Mounted upon the carriage 24 is a speaker motor assembly, designated generally by the numeral 65, which includes a coil 66, a core 67, a core pole structure 68, a permanent magnet 69, and an armature 70 on the upper end of which (Fig. 2) where is secured a printing element 71. The armature 70 is hinged to a clamping plate 72 by means of a flexible metal reed 73 whereby the surges of current in the coil 66 may cause the armature to vibrate and move the printing member 71 as will be described more in detail hereinafter. The printing member 71 is T-shaped in cross section as may be seen by reference to Fig. 2, and has formed on it a printing ridge or stylus 74 (Figs. 1 and 2) which will be driven into engagement with a web of paper 75 by the armature 70.

Suitably supported at the rear of the apparatus (the left side as viewed in Fig. 2) is a roll of paper 76 from which the web 75 may be drawn. Any suitable tensioning device (not shown) may be provided for imparting the proper tension to the paper which is drawn from the roll 76 and directed over a guide roller 77 journaled in the side plate 20 and 21. The web 75 is drawn over the roller 77 and directed upwardly past the stylus 74 to feed rollers 78. There are two feed rollers 78 provided in the apparatus, one of them adjacent to each of the side plates 20 and 21, and these feed rollers are mounted upon a shaft 79 which is adapted to be driven intermittently, the shaft 79 having a ratchet 80 positioned thereon for cooperation with a pawl 81. The pawl 81 is pivotally mounted upon the end of an armature member 82 and is spring biased to rotate in a counterclockwise direction with respect to armature member 82, which armature member is urged to rock clockwise about its pivot member 83 by a contractile spring 84. The pivot member 83 is mounted on the end of a bracket 85 (Fig. 1) extending inwardly from the side plate 20. A second bracket 86 also mounted on the side plate 20 supports an electromagnet 87 which upon ener-

gization will attract the armature 82 thereby to extend the spring 84, and upon the de-energization of the electromagnet 87 the spring 84 will drive the pawl 81 to the right (Fig. 2), and thereby impart rotation to the ratchet 80.

The web 75 is held in engagement with the feed rollers by spring pressed rollers 88 mounted on the upper ends of bell crank members 89. Inwardly extending arms 90 formed on the side plates 20 and 21 are interconnected with the horizontally extending arms of the bell cranks 89 by springs 91 thereby to urge the bell cranks 89 to rock in a counterclockwise direction, as viewed in Fig. 2, and carry the rollers 88 into engagement with their associated feed rollers 78, the rollers 88 being freely rotatable on the upper end of the arm of the bell crank 89. The bell cranks 89 are pivotally mounted on the inner surfaces of the side plates 20 and 21 by means of posts 92 being held on the posts by nuts 93.

Extending outwardly from the side plate 20 is a projection 100 on which there is pivotally mounted an ink transferring mechanism, comprising a U-shaped supporting frame 101, an ink supply roller 102 and an ink transfer roller 103. The ink supply roller and the ink transfer roller are suitably mounted for rotation on stud shafts 104 and 105 suitably journaled in the U-shaped frame member 101, and the U-shaped frame member 101 is mounted on a pivot stud 106 extending upwardly from the projection 100. A spring 107 serves to urge the U-shaped supporting frame 101 to rotate in a counterclockwise direction, as viewed in Fig. 1, thereby to carry the ink-transfer roller 103 into engagement with ridges 108 formed on the outer surface of a belt or tape 109.

An idler roller 115 and a driven roller 116 suitably mounted in U-shaped brackets 117 and 118 extending outwardly from the side plates 21 and 20, respectively, support the belt or tape 109 and drive it to carry the ridges 108 thereon across the face of the paper web 75 in timed relation to the travel of the carriage 24 and the rate of reciprocation of the stylus 74 under the control of the received signals. The driven roller 116 is mounted upon a shaft 119 which also carries driving gear 126 in mesh with gear 18 on shaft 13. Thus the belt 109 is driven at a speed proportional to the speed of travel of the carriage 24 across the web 50 of paper 75 in the direction of movement of the carriage, it being understood that the speed of travel of the belt or tape 109 is much more rapid than the speed of travel of the carriage 24, the speed of travel of the belt 109 being such that a straight line equal to the height of a letter being printed will be formed on the paper web 75 through the cooperation of the stylus 74 and the printing ridges 108 when the coil 66 is energized for the longest period under control of a received signal (corresponding to the height of a character). Extending across the front of the apparatus and between the side plates at 20 and 21 is a stiffening plate 120 which will hold the belt 109 in the position shown in Figs. 1 and 2 when the stylus 74 strikes against the paper and tends to bow the belt 109 toward the front of the machine.

Mounted on the right side (Fig. 3) of the side plate 20 is a contact assembly 121 comprising contacts 122 and 123 insulated from each other and from the side plate 20. The contact 123 constitutes the movable contact of the pair of contacts 122 and 123 and has an insulator 124 mounted at its upper end for an engagement by an actuating extension 125 formed on the carriage 24.

whereby the carriage 24 upon reaching the end of its travel to the left (Fig. 3, or the right in Fig. 1), will move the actuating extension 125 into engagement with the insulator 124 on contact member 123 thereby to close a circuit between contacts 122 and 123. The contact assembly 121 is connected in the circuit to electromagnet 87, and upon completion of a circuit through them will cause energization of electromagnet 87. The completion of a circuit through the contact assembly 121 will also supply an actuating current to the electromagnet 89. The electromagnet 89 may be made slow to release, or any other suitable means may be provided for delaying the release of this electromagnet after its energization to time its function properly as will be described hereinafter in connection with the description of the operation of the apparatus.

The system in which the apparatus described in detail hereinbefore is included, may comprise a transmitting apparatus and a receiving apparatus. The transmitting apparatus preferably is of the form disclosed in the copending application to R. E. Zenner, Serial No. 209,523, filed May 23, 1938, modified so that a carriage return period will be automatically provided in the transmission of a message from a transmitter such as that shown in the afore-mentioned application, and adapted to be received by a receiving apparatus such as that described hereinbefore. In the system forming a part of the present invention, as illustrated diagrammatically in Fig. 4, a radio frequency tape controlled transmitter of the same general type as that disclosed in said copending application, is provided in a modified form. As described in said copending application, a solenoid 131 controls the sensing of a tape 128 to operate a corresponding set of contacts 129, which control circuits to a series of selecting magnets of a code bar selector, through the instrumentality of which the brushes 127 are selectively operated to be brought into contactual engagement with associated transmitting code discs 133. In the said copending application, the circuit to the electromagnet 131 is completed once for each cycle of character transmission, a contact pair 132 being provided for this purpose. In the present invention, the character transmitting drum 133 is geared to the tape feed controlling cam drum 134 in such manner that the circuit to the electromagnet 131 will be held energized for a relatively long period of time after the transmission of a series of characters representing signals. As shown in Fig. 4, a gear 135 meshes with a much larger gear 136, and the gear 136 drives the cam drum 134 for controlling the open and closed period of the contact pair 132. It will be noted that the cam drum 134 is provided with a series of raised portions 138 which upon engagement with a cam roller 140 will cause a closure of the contact pair 132, and that a relatively wide angled raised portion 139 is provided for holding the contact pair 132 closed a relatively longer time than the raised portions 138. The length of the dwell or cam portion 139 is designed to be commensurate with the time required to effect the carriage return operation in the receiving machine, and as will presently appear, the phasing between the transmitter and receiver is such that the contact 123 is closed by the extension 125 on carriage 24, substantially simultaneously with the closing of contact 132 by the advancing end of long dwell or cam portion 139. The number of raised portions 138 may be varied in accordance with the width of paper on which the transmitted

messages are being typed at the receiving station, and while a certain number has been shown in the present disclosure, it will be understood that any number of raised portions 138 may be provided equal in number to the number of characters which may be printed on the page at the receiving station.

If it be assumed that the facsimile printer at the receiving station is in its normal position 10 where the carriage 24 is at its extreme left-hand position, the cam drum 134 should be in such position that the cam roller 140 has just passed off of the high portion of the cam surface or portion 139. With the apparatus in this condition, a 15 message may be transmitted by the transmitting apparatus and each time the cam roller 140 engages a raised portion 138 on the cam drum 134 the circuit to the electromagnet 131 will be closed, thereby to cause, as described in the afore-mentioned copending application, the tape at the transmitting station to be stepped forward to present a code combination of holes for controlling the transmitting apparatus. Transmission of a 20 message may thus proceed and if the proper number of raised portions 138 have caused the closure of the circuit through the electromagnet 131 a predetermined number of times, the actuating extension 125 on the carriage 24 at the receiving station will engage the insulator 124 thereby to 25 complete a circuit to the electromagnets 87 and 89 to restore the carriage 24 to its normal position, at the same time the portion 139 of the cam drum 137 engages the contact 132, interrupting the feeding of tape to the tape sensing portion of the 30 transmitting apparatus. It is observed that the carriage 24 is returned to the beginning-of-line position only after it has traveled the full width of the page and has engaged the contact 123. It is possible that a message will have been completed before the carriage 24 has reached said 35 position. In this event, the succeeding message will start at this point without having the carriage 24 returned to its beginning-of-line position. It is thus noted that a succeeding message is not 40 always started at the left-hand margin of the page (as viewed in Fig. 1), unless and/or until the carriage 24 is first permitted to move to the right-hand margin of the page to engage and close contact 123 to initiate simultaneously the carriage 45 return and line feed operations. As previously indicated, the dwell or cam portion 139 controls the cessation of transmission of intelligence signals during the performance of the carriage return function in the receiver. More specifically, 50 it is a requirement of the arrangement or system according to this invention that a predetermined phase relationship be established between the transmitter and the receiver, and this is achieved when the extension 125 on carriage 24 closes contact 123 while at the same time cam portion 138 55 is acting to close contact 132. So long as portion 139 is holding contact 132 closed, and while the carriage 24 is being returned to its beginning-of-line position, a series of blank signals is being 60 transmitted from the transmitter. At the receiver, as shown schematically in Fig. 4 at 141, the transmitted signals will be received and will control, after being demodulated, the circuit to a line coil 142 through which they are directed to ground at 143. The received signals are also directed over a conductor 144, through a winding 145 of a double wound relay 146 and then to ground. The line coil 142 and the winding 145 are accordingly connected in parallel. The radio 65 printer disclosed schematically in Fig. 4 con-

prises the printing stylus 74 which cooperates with the ridges 108 on the tape 109 and reciprocates with the line coil in response to received signals. The line coil 142 will respond to marking signals and force the stylus 74 against the paper to pinch the web 75 between the stylus 74 and the ridges 108 on tape 109 whereby the web 75 will be marked in accordance with received marking signals to record the characters. The other winding of the double wound relay 146 is connected to a locking circuit as described in said copending application of R. E. Zenner, Serial No. 209,523.

In the operation of the apparatus, signals transmitted by the transmitter shown in Fig. 4, will be received, and the tape at the transmitter (not shown) will be passed through the sensing mechanism (also not shown but fully disclosed in the said copending Zenner application), the feeding of the tape being controlled by the contact pair 132 to transmit a series of character representing signals corresponding in number to the number of raised portions 138 on the cam drum 134, and the tape feeding mechanism will be disabled temporarily during the rotation of the cam drum 134 by the engagement of the cam roller 140 with the portion 139 of the cam drum 134. The signals transmitted by the transmitter will be received in the radio frequency receiver 141, demodulated, and the signals impressed on the line coil 66 thereby to cause the printing stylus 74 to reciprocate, and in cooperation with the ridges 108 on the tape 109 effect printing on the web of paper 75. As the cam drum 134 reaches the position where the portion 139 thereof will engage the cam roller 140, the carriage 24 will have traveled to its extreme position, and the extension 125 thereon will close the circuit between contacts 122 and 123 to complete a circuit to electromagnets 39 and 87. Energization of electromagnet 87 will extend the spring 84 and prepare the ratchet 80 for operation by its associated pawl 81 upon the release of the electromagnet 87. Electromagnet 87 upon its release will permit the spring 84 to drive the ratchet 80, and in turn impart rotation to the paper feed roller 78 thereby to advance the paper a predetermined amount and effect line spacing. The energization of electromagnet 39 will disengage the driven clutch member 33 from the driving clutch member 50 on shaft 51. Upon release of the driving and driven clutch members 50 and 33, the spring motor 41 mounted on bracket 43 will be permitted, through strap 42, to draw the carriage 24 back to its starting position, thus effecting carriage return and line spacing at substantially the same instant.

Although a specific embodiment of the invention has been described hereinbefore, it will be understood that numerous modifications and adaptations thereof may be made without departing from the scope of the invention which is to be limited only by the scope of the appended claims.

What is claimed is:

1. In a facsimile telegraph system, a transmitter, a receiver including a signal responsive speaker motor translatable across one face of a web of paper, a scanning tape translatable across the opposite face of said web of paper and adapted to cooperate with said motor to effect printing, means for depositing marking material on said tape, and means for driving said tape and said motor translating means in synchronism with said transmitter, whereby a printed record is made on said web in accordance with the vi-

bratory response of said motor to received signal impulses.

2. In a facsimile telegraph system, a receiver including a speaker motor translatable across the rear face of a web of paper, a scanning tape having ridges thereon translatable across the front face of a web of paper and adapted to cooperate with said motor to effect printing, means for driving said tape and said motor in their translation in the same direction at predetermined proportionate speeds, and means effective upon a predetermined movement of said motor for disconnecting said motor translating mechanism from its driving source, whereby said motor may be returned to an initial position.

3. In a facsimile telegraph system, a receiver including a ridged tape movable across the front face of a web of paper, a speaker motor actuated platen responsive to received signals movable across the rear face of a web of paper and adapted to cooperate with said tape to effect printing, means for applying marking material to the ridges on the tape, and means effective automatically upon a predetermined movement of said speaker motor for returning the speaker motor to its initial position.

4. A printing telegraph receiver comprising means actuated in response to received signals, means for moving a web of paper through a predetermined path, means movable across the web of paper between the paper and the means actuated in response to signals, and means cooperating with the means movable across the paper and positioned on the side of the paper away from the means movable across the paper and cooperating therewith to pinch the paper and mark it upon receipt of a signal.

5. In a facsimile recorder, the combination of a stylus member having a plurality of straight line stylus edges, means for manipulating the stylus member to move the stylus edges rapidly through a predetermined zone, a vibratory ridged means slowly movable across said zone, and signal responsive means for vibrating said vibratory ridged means.

6. In a facsimile recorder the combination of a stylus member having a plurality of straight line stylus edges, means for manipulating the stylus member to move the stylus edges rapidly through a predetermined zone, a vibratory ridged means slowly movable across said zone, means for drawing a sheet of record material over the said stylus member, and signal responsive means for vibrating the ridged means to compress and mark the record material between the stylus member and ridged means.

7. In a facsimile telegraph system, a transmitter having a transmitting element for each character, each element having a single line of signal controlling portions thereon corresponding to a scanning of its character, means for directly recording a facsimile of a selected character by signals received from its transmitting element, said means including a receiving element operable in synchronism with the transmitter, rack and pinion means for controlling the movement of said means in one direction, function performing means, a clutch for controlling the power supplied to said rack and pinion means, an electromagnet for controlling said clutch, a circuit for said electromagnet, a contact in said circuit, means carried by said receiving element effective at one operable position of said element for operating said contact to effect the energization of said electromagnet to

condition said clutch for releasing said receiving element for reverse movement under control of said function performing means, and means in said transmitter for interrupting operation of the transmitter at predetermined intervals to provide automatically an interval of sufficient duration to assure complete operation of said function performing means.

8. In a facsimile telegraph system, a transmitter having a perforated control member, a plurality of feeler fingers engageable with said perforated member and selectively positioned in accordance with the perforations therein, a plurality of transmitting elements each having signal impulse controlling portions corresponding to a scanning of a character, means effective under the control of said feeler fingers for transmitting signal impulses by one of said elements, means for directly recording a facsimile of a selected character controlled by said signals, said means including a receiving element operable in synchronism with said transmitter, rack and pinion means for controlling the movement of said means in one direction, function performing means; clutch means for controlling the power supplied to said rack and pinion means, an electromagnet for controlling said clutch, a circuit for said electromagnet, contact means in said circuit, means carried by said receiving element effective at one operable position of said element for operating said contact to effect the energization of said electromagnet to condition said clutch means for releasing said receiving element for reverse movement under the control of said function performing means, and means in said

5

transmitter for interrupting operation of the transmitter at predetermined intervals to provide automatically an interval of sufficient duration to assure complete operation of said function performing means.

10

9. In a facsimile recorder, the combination of a stylus member having a plurality of straight line stylus edges, means for operating the stylus member to move the stylus edges rapidly through a predetermined zone, a platen slowly movable across said zone, and signal responsive speaker motor means for vibrating said platen.

15

10. In a facsimile telegraph recorder, the combination of a stylus member having a plurality of straight line stylus edges, means for operating the stylus member to move the stylus edges rapidly through a predetermined zone, a platen slowly movable across said zone, means for drawing a sheet of record material over said stylus member, and signal responsive speaker motor means for actuating the platen to compress and mark the record material between the stylus member and platen.

20

11. A printing telegraph receiver comprising speaker motor means responsive to received signals, means for moving a web of paper through a predetermined path, a platen adapted to be moved across the web of paper between the paper and the speaker motor means, and means cooperating with said speaker motor means and positioned on the side of the paper away from the platen and cooperating therewith to pinch the paper and mark it upon receipt of a signal.
